UNITED STATES PATENT OFFICE.

BENJAMIN F. MAYO, OF SALEM, MASSACHUSETTS, ASSIGNOR, BY MESNE ASSIGNMENTS, TO THE UNITED SHOE MACHINERY COMPANY, A CORPORATION OF NEW JERSEY.

NAIL-ASSORTING APPARATUS.

SPECIFICATION forming part of Letters Patent No. 707,137, dated August 19, 1902.

Application filed October 28, 1898. Serial No. 694,780. (No model.)

To all whom it may concern:

Be it known that I, BENJAMIN F. MAYO, of Salem, county of Essex, State of Massachusetts, have invented an Improvement in Nail-5 Assorting Apparatus, of which the following description, in connection with the accompanying drawings, is a specification, like characters on the drawings representing like parts.

This invention has for its object to improve 10 nail-assorting apparatus whereby the nails may be assorted as to heads and points while traveling on the raceway and the assorted nails arriving at the lower end of the raceway with their heads all pointing in the same direction are received on a device from which they may be delivered either head or point first. Heretofore in this class of machine 15 nails came to the end of the raceway with their heads and points arranged indiscriminately and said nails slid into position upon a lifter which has been moved to take bodily with it the nails lying upon it and put them in other grooves, as of a raceway-terminal, from which they descend to an assorting device or 20 nail-controller, it being adapted to receive immediately all the nails leaving the raceway-terminal head first, the nail-controller, however, arresting the nails coming to it from said terminal point first, and thereafter by 25 imparting an additional movement to the controller or a part operatively combined with it the point-first nails so temporarily arrested are permitted to slide farther longitudinally sufficiently to remove their heads or heavier 30 ends from the raceway-terminal, after which said nails also enter grooves in the nail-controller. The nails assorted with their heads all in one direction and lying in the grooves of this controller are thereafter discharged 35 40 with their heads all in the same direction.

I have aimed to simplify this class of machine, and I have done so by omitting the lifter and the raceway-terminal, and instead I have so constructed the raceway that the 45 nails arriving at its lower end are so arranged that their heads all point in the same direction, said nails assorted as to the direction of their heads coming upon a device which is thereafter moved to deliver directly into suitable 50 pockets the nails received upon the said

device. In my improved raceway I arrange its grooved parts in different levels and provide at the discharge end of the uppermost level a transverse shoulder, beyond which is a space in which all the nails in the grooves 55 of the raceway which are arranged head first drop by gravity, said nails thereafter continuing to slide down the lower part of the raceway with their heads leading; but all the nails which are deposited in the grooves of 60 the raceway above said shoulder point first on arriving at said shoulder cross the space and enter grooves of a nail-point receiver, and said point-first nails continue to travel until their heads pass the shoulder referred 65 to, when the heavier head ends of the nails preponderating immediately turn the said nails end for end, letting them drop into the grooves of the lower part of the raceway head first, they continuing to travel in the lower 70 part of the raceway head first. In this way it will be noticed that the raceway itself has provisions whereby it acts automatically to assort as to heads and points the nails which come down its grooves. Herein the nails, all 75 arranged with their heads in one direction at the lower part of the raceway proper, pass therefrom with their heads all in one direction upon a device which I may move at the proper times and in either direction to discharge said assorted nails head first or point first into pockets which lead to the position from which they are to be driven.

In devices of this class as heretofore constructed it has been customary to reciprocate 85 the raceway constantly in order to work the nails gradually down to the delivery-point, and in order to insure the separation of a series of nails at each operation of the device which transfers the nails from the raceway it 90 has been customary to divide the raceway near its lower end, placing its lower portion higher than the other part, and to employ a lifter to elevate a series of nails from one portion of the raceway to the other, thus separating at each operation a series of nails to be acted upon by the transferring device. This construction involves a great deal of expense and necessitates mechanism which is likely to get out of order and to become 95 100

clogged with nails and slivers. In my construction I have been able to dispense with this division of the raceway and with the lifter, and I have done this by the use of 5 mechanism for stopping the reciprocations of the raceway at each operation of the transferring device, so that while the transerrer is operating there is no reciprocation of the raceway, and consequently there is no movement of the nails toward the transerrer and no confusion of each series of nails as they are being handled with the preceding nails on the raceway.

I believe I am the first to arrange in a nail-assorting mechanism means for intermittently stopping the reciprocations of the raceway and so stopping the movement of the nails thereon when desired.

The device employed by me to receive and 20 deliver the nails is represented as a table, which may be oscillated, preferably, in one or the other direction at will.

Figure 1, in side elevation and partially broken out, represents a sufficient part of a 25 nail-assorting apparatus with my improvements added to enable my invention to be understood. Fig. 2 is a section in the line x , Fig. 1. Fig. 2^a is a detail of the clutch part D⁶ detached from the machine. Fig. 3 is a 30 top or plan view of the apparatus shown in Fig. 1. Fig. 4 is a view of the apparatus looking at the receiving or left-hand end. (See Fig. 3.) Fig. 5 is a sectional detail in the line x' , Fig. 3. Fig. 6 is a sectional detail in the line x^2 , Fig. 3. Fig. 7 is a detail showing the nail receiving and delivering device in section, together with the end of the overflow-pan.

The base-frame A, of any usual or suitable 40 shape, has guideways A', overlapped by gibs A², said guideways receiving the lower end B of a reciprocating frame B'. The frame B' has connected to it within its sides by screws B³ an overflow-pan B³, (see Fig. 4,) 45 said pan being provided with a lug or ear B⁴, to which is jointed a link B⁵, having at one end an eccentric-strap, (see Fig. 1,) which embraces an eccentric B⁶, fast on a rotating shaft B⁷, said shaft being run at a high speed, 50 preferably a speed of about nine hundred revolutions per minute, so that said frame B' is reciprocated very rapidly. The base-frame contains bearings for said shaft and also for a driving-shaft C in line with it, the shaft C 55 having a fast pulley C', which receives a belt, so that said shaft is rotated continuously. The shaft C has a worm C², which engages a worm-toothed gear C³, fast on a shaft D, sustained in bearings D' D², carried by the base 60 A. The shaft D has a bevel-pinion D³, which engages a bevel-pinion D⁴, fast on a shaft D^X, said shafts C and D each having a suitable disk C⁴ D⁵, each concaved at its face and forming part of a friction-clutch, the coöperating 65 parts C⁵ D⁶ of said clutches being fast, respectively, on the shafts B⁷ and D⁷. Both the disks C⁴ and D⁵ rotate continuously; but only

one of said shafts B⁷ and D⁷ is rotated at the same time, and which shaft is to be rotated is determined by a clutch-lever E, to be described, it being pivoted at E' and being normally retained by a suitable spring E² in such position that the clutch C⁴ C⁵ is in engagement and the clutch D⁵ D⁶ open, the shaft B⁷ being rotated. Each clutch part C⁵ and D⁶ 75 has its periphery cut (see Fig. 2^a, where D⁶ is shown detached) to present radial shoulders, as 2 and 3, and one side of each of said parts is cut away near said shoulders to leave inclined surfaces, (see Fig. 3,) said surfaces 80 being shown as oppositely inclined, against which may act the inclined ends of said clutch-lever, said inclined ends working in advance of the action of the shoulder, the latter effecting a full stop of the shaft when engaged 85 by the shouldered end of the clutch-lever. The two shafts B⁷ and D⁷ are free to slide in their bearings, and when the clutches are closed they slide in one direction and in the opposite direction when they are opened. 90 These shafts have each a spring, as a, acted upon by a plunger a', said plungers being held in adjusted position by suitable adjusting-screws a², shown as held in a bar a³. The sliding frame receives and supports a 95 raceway, represented as composed of a receiving-section F and a secondary section F', the section F being represented as located in a higher plane than the section F'. The receiving-section has at its upper extremity several wide grooves f, which have communicating with them narrower grooves f³, deeper cut, the ends of the grooves f³ terminating at the shoulder f¹⁰ at one end of the receiving-section, said shoulder being extended 100 across the raceway, so as to leave a space b across the raceway, so as to leave a space b at the end of said shoulder. The lower or secondary section F' has grooves b', which are made in continuation of the grooves f³, and all nails that enter the grooves f and get 105 into the grooves f³ continue to travel along in the grooves b'; but the nails which come into the grooves f when the nails are applied in bulk to the part F of the raceway and do not get into the grooves f³ drop through 110 the spaces f' into the overflow-pan and run back to the source of supply for the nails. The nails get into the grooves f³ heads and points indiscriminately; but whenever nails having their heads leading arrive at the shoulder f¹⁰ such nails, their heads predominating, turn quickly down into the space b and enter the grooves b' of the lower section F' of the raceway. On the contrary, however, the 115 nails which get into the grooves f³ point first continue to travel in said grooves until their points enter the grooves b³ of the nail-point receiver b⁴, said nail-point receiver being adjustable toward and from said shoulder by or through suitable adjusting-screws b⁵, the said 120 nail-point receiver being adjusted toward and from said shoulder, according to the length of the nails being acted upon. The nails the 125 points of which enter the grooves of the nail-

point receiver finally travel far enough so that their heads leave the shoulder f^{10} and immediately thereafter, the said heads preponderating, drop down into the space b , and the said nails are completely overturned or reversed end for end, they entering the grooves b' and thereafter traveling head first therein. The ends of the grooves f^3 are widened and the breast of the shoulder f^{10} is somewhat curved, and the grooves b' are made in the breast of said shoulder substantially up to and to join the grooves f^3 , so that there is little, if any, liability of the nails when they drop into the space b getting out of position so that they will not thereafter follow along down the raceway in the grooves b' .

It will be observed that the receiving-section F of the raceway, which receives the nails in bulk with their heads and points arranged indiscriminately, is not so much inclined from the horizontal as the lower or secondary section F'. I have found this arrangement necessary because, first, the nails are placed in bulk on the upper or receiving section F, and it is not necessary to accelerate their movement, as is the case when the nails are on the lower or secondary section F', and, secondly, it is important to have the lower section at a greater inclination, because as the nails are arranged in single lines in narrow grooves it is necessary to accelerate their movement in order to insure a sufficient supply at the delivery end of the raceway. It would not be practicable to have the receiving-section F of the raceway at the same inclination as the secondary section F', because there would be danger that the momentum of the nails leaving the receiving-section F at the shoulder f^{10} would carry all the nails, particularly the head-first nails, across the space b and upon or entirely over the nail-point receiver b^4 , so that the proper delivery of nails to the secondary section F' and the arranging of the nails with their heads first would be prevented.

Near the lower end of the raceway I have located a device for receiving and delivering the nails. I have lettered the said device G, and it has a series of narrow grooves b^2 , in which may enter the nails coming from the grooves b' of the raceway, the heads of the nails entering the groove b^2 meeting a suitable stop H, which may be adjusted relatively to the said device by means of set-screws H^1 . This device has a series of wide grooves m between the narrow grooves b^2 , so that any nails which may get into the wider grooves may slide therefrom while the device is stationary into the overflow-pan B^3 . This device may be designated well by the term "table," it having at its end suitable journal supports g , the said supports being preferably fixed to and extended from the table, the journals taking their bearings in the sides.

The device for receiving and discharging the nails has connected to one of its journals g a lever g' , each end of which is adapted, as

by a hole g^2 , to receive a screw g^3 , extended through one end of a link g^4 , the opposite end of said link being connected with a lever g^5 , having its fulcrum at g^6 , said lever having, as shown, a connected spring g^7 , which acts normally to keep said lever against a stop g^8 . The lower end of the lever g^5 stands normally in the path of movement of a cam g^9 , and at such time the clutch-lever E is in engagement with the clutch part D⁶ and the table or device G to receive and discharge the nails is held at rest. The clutch parts D⁵ and D⁶ may, however, be released by moving the clutch-lever through a suitable rod h whenever it is desired to deliver the series of nails then lying on the table, and when the clutch parts are so connected the cam g^9 will engage lever g^5 and through link g^4 will turn table G to deliver the nails. When the link g^4 is connected to the lower end of the lever g' , the cam g^9 will act to tip the table over toward the right and will deliver the nails having their heads then in contact with the stop H, head first into the pockets H^2 , there being one such pocket for each nail, all said pockets having in practice connected to them suitable guideways, tubes, or devices to lead said nails to the point where they are to be driven. The series of pockets is held in place by suitable set-screws H^4 , one of which is shown in Fig. 1. The points of the nails deposited on the table lie substantially in and cross the space h^3 . To tip said table so that all the said nails lying thereon with their heads leading may be delivered point first into the pockets H^2 , I adjust the series of pockets into the dotted-line position, Fig. 1, and change the screw g^3 into the hole at the upper end of the lever g' , and thereafter the movement of the lever g^5 will insure that the table tips over toward the left, letting the nails thereon slide off point first through the space h^3 into the pockets in their changed positions.

In practice the clutch, composed of the parts C⁴ C⁵, is closed for most of the time, and the plate F is reciprocated to keep all the grooves referred to filled with nails; but whenever a series of nails on the table G is to be discharged therefrom then the clutch-lever is operated to close the clutch D⁵ D⁶ to start the shaft D⁷ to thereby tip or rock the table, as described, the reciprocations of the plate F being arrested by disengagement of clutch parts C⁴ C⁵ through lever E, as hereinbefore explained, while the table is being tipped, so that the nails on said plate and the plate F' will remain at rest, and there is no chance for the nails on the plate above the table to escape from said plate.

It will be noticed that the stop g^8 arrests the lever g^5 , so that its edge next the cam g^9 stands at a short distance from said cam, so that as the frame B' is reciprocated the said lever will not bump against said cam, which might keep the table G in motion somewhat about its trunnions.

This invention is not limited to the par-

ticular shape of the grooves in the raceway nor to the particular number of grooves, as there may be more or less, according to the number of nails it is desired to simultaneously feed at one operation into position to be driven. It should further be understood that while in the mechanism which is herein shown and described all the features of my invention have been embodied it would nevertheless be possible to secure many of the advantages of my invention in machines embodying only a portion of the invention and not all of its features, and such machines would be clearly within the scope of my invention.

Having fully described my invention, what I claim, and desire to secure by Letters Patent, is—

1. A grooved raceway having provision to automatically assort the nails entering the upper runs of its grooves head and point first indiscriminately, and put said nails into the lower parts of said grooves all head first, combined with a device to receive the endmost nails, a stop to position said nails on said device, a series of pockets to receive and conduct the assorted nails, and means to move said device to deliver the nails coming upon it directly from the raceway into said pockets, substantially as described.

2. A raceway presenting a series of continuous grooves in two levels inclined in the same direction and having a transverse groove between said levels to form a series of shoulders, the upper level receiving nails with their heads and points arranged indiscriminately; and a nail-point receiver crossing the grooves of said lower level whereby those nails which are head first continue to travel forwardly into the grooves of the lower level of the raceway, the nails with their points leading in the grooves of the higher level crossing said transverse groove until their heads leave said higher level, when said nails are reversed and thereafter continue to travel forwardly in the grooves of the lower level of the raceway.

3. In a nail-assorting mechanism, a raceway to receive and guide nails, means to reciprocate said raceway, a device to transfer nails from said raceway, mechanism for actuating said device to transfer nails, and means for stopping the reciprocations of the raceway while said transferring device is being operated.

4. In a nail-assorting apparatus the following instrumentalities, viz: a raceway, a device located near the lower end thereof to receive the nails from said raceway, an independent stop to position the nails on said device, and means to tip the said device to effect the discharge of the nails therefrom, substantially as described.

5. In an apparatus of the class described, a raceway to receive, conduct, and deliver nails head first, a series of pockets to receive said nails, a grooved table located intermediate

the delivery end of said raceway and the said pockets to receive all said nails head first, and a stop to position the nails thereon, combined with means to tip said table to effect the discharge of its nails into said pockets, substantially as described.

6. A raceway adapted to receive and guide nails, a series of pockets in which the assorted nails are finally to be discharged, combined with a device located intermediate the said raceway and the said pockets to receive said nails, an independent stop to position said nails on said device, and means to actuate said device to deliver the nails into said pockets either head first or point first, substantially as described.

7. In an apparatus of the class described, a raceway to receive and conduct nails, a series of adjustable pockets, and a device located between said raceway and adjustable pockets to receive the nails from said raceway, and means adapted to be changed as to position to tip said device in either direction when it is desired to deliver the nails therefrom either head first or point first, substantially as described.

8. In an apparatus of the class described, a stop to receive against it the head of a nail after the same has crossed a grooved table, a grooved table having journals, a cam, and means intermediate said cam and one of said journals to oscillate said table to effect the discharge of nails therefrom, substantially as described.

9. In an apparatus of the class described, a raceway grooved to conduct nails, said raceway having provision to assort the nails put into said groove with heads and points indiscriminately, so that said nails may follow in a continuation of said groove head first, a grooved table to receive the nails head first, a pocket, a cam, means to actuate it, and means actuated by said cam to tip said table and effect the discharge of the nails therefrom, substantially as described.

10. In a nail-assorting apparatus, the following instrumentalities, viz: a raceway having its surface at different levels and provided with continuous grooves, and having a shoulder to leave a transverse space intermediate the two ends of said grooves, an adjustable nail-point receiver located near the said shoulder and below the said transverse space, combined with a device to receive the nails assorted on said raceway head first, and a stop to position the said assorted nails on said device, and means to actuate said device to discharge the nails therefrom, substantially as described.

11. In a nail-assorting apparatus, the following instrumentalities, viz: a raceway to receive and guide a series of nails, a rotating shaft having a clutch adapted when in operative engagement therewith to effect the reciprocations of said raceway, a device to receive a series of nails from said raceway, a second shaft having a clutch, means inter-

- mediate said second shaft and the device for receiving said series of nails to effect the discharge of said series of nails from said device when the latter clutch is engaged, and means 5 whereby when one of said clutches is in its operative position to rotate one of said shafts, the other of said clutches will be disengaged to leave at rest the shaft with which it co-operates, substantially as described.
- 10 12. A raceway to conduct nails, a tipping table to receive nails from said raceway, an independent stop for the ends of the nails leaving said raceway and coming onto said table, combined with a series of pockets, and 15 means to tip the said table and cause one edge thereof to pass below the level of the delivery end of said raceway in order that the nails on said table may slide therefrom into said pockets, substantially as described.
- 20 13. A raceway to receive and guide a series of nails, a device arranged at the lower end thereof and provided with a double set of nail-receiving grooves, one being wider than the other, the narrower of said grooves 25 receiving nails from said raceway which are to be utilized, a stop to position said nails on said device in its narrower grooves, an overflow-pan, a series of pockets, and means to actuate said device whereby the nails left in 30 the broader grooves enter the overflow-pan, the nails which lie in the narrower grooves entering said pockets, substantially as described.
- 35 14. In a nail-assorting apparatus, the following instrumentalities, viz: a raceway to receive and guide a series of nails, a rotating shaft having a clutch and adapted to effect the reciprocations of said raceway when said clutch is in engagement with said shaft, a device 40 to receive the nails from said raceway, means to actuate said device and means to arrest the reciprocations of said raceway while the said device is being actuated to discharge from it the nails thereon, substantially as described.
- 45 15. A raceway adapted to receive and guide nails, means to reciprocate said raceway, a device to receive nails from said raceway, means to actuate said device to deliver nails, 50 and means to stop the reciprocation of the raceway during the delivery of nails, substantially as described.
- 55 16. A raceway adapted to receive and convey nails, means to cause the nails all to point the same way on said raceway, a device to transfer the nails from said raceway, and means to operate said device whereby the 60 nails may be delivered therefrom either head first or point first, substantially as described.
- 60 17. A raceway composed of a grooved plate having its surface in two different levels to thereby constitute an upper and a lower section, said raceway having a transverse groove or space to leave a shoulder, said sections 65 having nail-conducting grooves in line, the said grooves being deepest at said shoulder, combined with a nail-point receiver crossing

the lower section of said raceway above the grooves and below said shoulder, to operate, substantially as described.

70 18. In a nail-assorting mechanism, an inclined raceway to receive and guide nails, means to reciprocate the raceway and cause the nails to descend, and means for intermittently stopping the reciprocation of the raceway to arrest the forward movement of the 75 nails.

19. In a nail-assorting mechanism, a raceway to receive and guide nails, means to reciprocate said raceway, a device to transfer 80 nails from said raceway, mechanism to actuate said device to transfer nails, and means controlling said reciprocating means and said actuating mechanism whereby one is made inoperative when the other is operative.

85 20. In a nail-assorting mechanism, a raceway to receive and guide nails with their heads and points arranged indiscriminately, means to cause said nails all to point the same way on said raceway, a device to transfer the 90 nails from said raceway, and means to actuate said transferring device to deliver nails.

21. In a nail-assorting mechanism, a nail-controller grooved to receive nails, and means to actuate said controller whereby it may be 95 made to deliver the nails from its grooves either head first or point first.

22. In a nail-assorting mechanism, means to guide and direct a series of nails, a device to receive said series of nails therefrom at 100 one operation, and means to actuate said device whereby it may be made to deliver the nails either head first or point first as may be desired.

105 23. In a nail-assorting mechanism a raceway, a device to transfer nails from the raceway, means to reciprocate the raceway, and means for intermittently stopping the reciprocation of the raceway while the transferring device operates.

110 24. In a nail-assorting mechanism, a raceway presenting nail-guiding grooves arranged at different levels, the upper level of the raceway receiving nails with their heads and points arranged indiscriminately, means between said levels to reverse some of the nails to insure that all the nails on the lower level of the raceway may have their heads all in the same direction, means to reciprocate said raceway to cause the nails to travel thereon, 115 and a device under the control of the operator to omit a stroke of the raceway leaving the raceway at rest temporarily when it is desired to stop the movement of the nails on the raceway.

120 125 25. In a nail-assorting mechanism, a raceway presenting nail-guiding grooves arranged at different levels, the upper level of the raceway receiving nails with their heads and points arranged indiscriminately, means between said levels to reverse some of the nails to insure that all the nails on the lower level of the raceway may have their heads all in the same direction, means to reciprocate said

raceway, and a device under the control of the operator to omit a stroke of the raceway to leave the raceway at rest temporarily, and means for moving said device to start again 5 the reciprocation of said raceway.

26. In a nail-assorting mechanism, a raceway to receive nails with their heads and points arranged indiscriminately and having provision to arrange all said nails during their 10 travel along said raceway with their heads in the same direction, means to reciprocate said raceway to cause the travel of nails thereon, a device located at the end of said raceway to receive and sustain a series of nails delivered from the raceway, and means to stop 15 the reciprocation of said raceway while the series of nails is discharged from said device.

27. In a nail-assorting mechanism, a raceway having an inclined receiving-section to 20 receive and guide nails with their heads and points arranged indiscriminately and having

a secondary section at a greater inclination, means for causing the nails to travel on said raceway, and means for causing the nails delivered from the receiving-section to point 25 all in the same direction on the secondary section.

28. In a nail-assorting mechanism, an inclined raceway to receive and guide nails, means for causing the nails to move down 30 said raceway, means for causing said nails all to point the same way on said raceway, a device to transfer the nails from said raceway, and means to actuate said transferring device. 35

In testimony whereof I have signed my name to this specification in the presence of two subscribing witnesses.
